CLAIM

The ornamental design for a torque converter sprag clutch retainer, as shown and described.

DESCRIPTION

FIG. 1 is a bottom perspective view of the torque converter sprag clutch retainer showing my new design;

FIG. 2 is a top perspective view of the torque converter sprag clutch retainer;

FIG. 3 is a bottom view of the torque converter sprag clutch retainer;

FIG. 4 is a top view of the torque converter sprag clutch retainer;

FIG. 5 is a side view of the torque converter sprag clutch retainer;

FIG. 6 is another side view of the torque converter sprag clutch retainer from the side opposite of the side view of FIG. 5;

FIG. 7 is another side view of the torque converter sprag clutch retainer from a different perspective than that shown in FIGS. 5 and 6; and,

FIG. 8 is another side view of the torque converter sprag clutch retainer from the side opposite of the side view of FIG. 7.
